UNITED STATES PATENT OFFICE.

CURT STEDEFELD, OF HEIDELBERG, GERMANY.

VEHICLE CARRYING RAIL, IN PARTICULAR FOR HIGH-SPEED SUSPENDED-VEHICLE RAILWAYS.

Application filed May 16, 1928, Serial No. 278,131, and in Germany October 24, 1925.

The object of this invention is a vehicle-carrying rail arrangement which so holds the rail ends on the occurrence of a rail breakage that derailing is avoided. When a rail breakage occurs it is possible for the two ends to move relatively a considerable distance both vertically and horizontally. The invention has for its object such a constraint of the rail at any possible breakage that there can be no important difference in height between the broken rail ends: provision is also made to prevent relative lateral movement of the broken ends. The broken ends are therefore held together at the break to a sufficient extent to allow the wheels of the vehicles to pass over the break without danger of derailment.

Though not confined thereto, the invention is particularly designed for use in suspended vehicle railways operating at high speeds for example 300-500 km. per hour. In such high speed railways the weight of the rails must be kept low so as to obtain as smooth riding as possible. To avoid gaps, the rail joints are either welded or pressed together endwise by suitable means, so that the gaps are completely closed. To reduce the weight, the supports of the rails in suspended vehicle railways are arranged at greater intervals than in standing railways, where the rails are borne on sleepers. When a rail breakage occurs in such a suspended high speed railway, a considerable gap may be formed. The free end on being run over by a wheel strikes the undeflected end with a very violent blow. If the rail ends are also relatively displaced laterally there is considerable risk of derailment of the vehicle.

In order to avoid the danger of derailment, according to the invention the rail itself is provided with the following features. The rail cross section is weakened at certain intervals, so that any breakage will occur at one of these weakened places. The course of the breakage is defined by the shape of this weakening in such a manner that a pin and socket effect is obtained which couples the rail ends vertically. Advantageously the weakening extends over the web of the rail, but in some circumstances it can also extend over the head and foot. Holding of the rail ends together laterally is effected by guide plates which are laid on both sides of the rail web and held together by rivets, bolts or the like.

An example of such a rail which can be used in a high speed suspended vehicle rail-

way, is shown in the accompanying drawings.

In the drawings, Fig. 1 is a front elevation of a section of a rail constructed in accordance with the invention;

Fig. 2 is a transverse section of a rail constructed as in Fig. 1; and

Fig. 3 is a transverse section of a rail constructed with guide plates of U-form cross-section.

As Figure 1 shows, on both sides of the web ⁶⁵ *b* of the rail *a* at short distances apart and in similar positions, angle grooves *c* are rolled, the vertices of which are at the centre of the web and the limbs of which extend towards the rail head and foot. If now a break occurs in the rail *a*, for example at *e*, the line of breakage will follow the rolled grooves as shown in the drawing. There is formed therefore a pin-like web piece *f* which engages in an opposite socket-like recess of the ⁷⁰ other broken rail end, and any considerable relative vertical movement of the rail ends is prevented.

Naturally the weakening grooves can be ⁸⁰ other than V shaped; for example they can be trapezium shaped, right angular or curved. It is further advantageous to provide holes *d* at the ends and vertices of the weakening grooves, since by this means the course of a possible breakage is more certainly predetermined.

In order to prevent relative lateral movements of the broken rail ends, short guide plates *g* are arranged next to one another in staggered formation on opposite sides of the rail and secured by rivets or bolts *h* or in some other manner. The securing holes in the web are preferably elongated so that on the occurrence of a breakage a certain degree of longitudinal movement of the rail web relative to the guide plates is possible.

Instead of rectangular, as in Figure 2, the guide plates *g* can have some other cross section. In Figure 3 a U-form cross section is shown for example. If these guide plates are ¹⁰⁰ arranged on the rail so that only a slight gap is left at *k*, then in addition to an increased moment of resistance of the guide strip with the same weight, a further security against relative vertical movements of the broken ¹⁰⁵ rail ends is provided.

I claim:

1. A vehicle carrying rail, particularly for high speed suspended vehicles, in which the web of the rail is weakened at intervals by ¹¹⁰

a series of recesses so that any breakage of the rail will follow the line of weakening defined by the said recesses, said recesses being so shaped that the broken ends of the rail will 5 interlock and each support the other.

2. A vehicle carrying rail, particularly for high speed suspended vehicles, in which the web of the rail is weakened at intervals by a series of recesses so that any breakage of the 10 rail will follow the line of weakening defined by the said recesses, said recesses being so shaped that the line of breakage returns on itself in the longitudinal direction of the rail.
- 15 3. A vehicle carrying rail as defined in claim 1, in which guide plates are secured

on both sides of the web by rivets, bolts or the like, in order to prevent relative lateral movement of the rail ends in the event of a breakage.

4. A vehicle carrying rail as defined in claim 1, in which guide plates are secured on both sides of the web by rivets, bolts or the like, in order to prevent relative lateral movement of the rail ends in the event of a breakage, and in which said guide plates extend close up to the rail head and foot so that they also limit the possible relative vertical movement of the broken rail ends.

In testimony whereof I have affixed my 30 signature.

CURT STEDEFELD.
